DECORATIVE PANEL FOR CIGARETTE LIGHTERS AND THE LIKE

Jerome Hammer, New York, N.Y., assignor to Panation
Trade Company of New York, New York, N.Y.

Application January 13, 1958, Serial No. 49,214

Term of patent 14 years

(Cl. D48—27)

Fig. 1.

Fig. 2.

Fig. 1 is a view in side elevation of a decorative panel for cigarette lighters, the broken lines being for illustrative purposes only.

Fig. 2 is a view in section of the decorative panel taken on the line 2—2 of Figure 1.

I claim:

The ornamental design for a decorative panel for cigarette lighters and the like, as shown and described.
